UNITED STATES PATENT OFFICE.

ELROY A. CHASE, OF NORTHFIELD, VERMONT.

APPARATUS FOR PRODUCING ORNAMENTAL BACKGROUND ON STONE.

Application filed April 23, 1926. Serial No. 104,193.

This invention relates to apparatus for use in producing an ornamental background in sand blast work on granite or other similar stone.

5 In producing such work, difficulty has been encountered in securing a satisfactory contrast between the background and the raised design, particularly when using one of the lighter colored granites. An improved method of producing a contrasting background has been invented and previously patented by Sanborn and Haslam, No. 1,500,272, dated July 8, 1924.

It is the object of my present invention 15 to provide certain improved apparatus adapted to be used in the Sanborn and Haslam process.

My invention relates more specifically to the provision of an improved form of sand 20 obstructing device or screen to be interposed in the path of the sand blast and thus assist in producing a contrasting surface on the background.

My invention further relates to certain 25 arrangements and combinations of parts which will be hereinafter described and more particularly pointed out in the appended claims.

Two forms of the invention are shown in 30 the drawings in which

Fig. 1 is a plan view of one form of the invention;

Fig. 2 is a transverse sectional elevation, taken along the line 2—2 in Fig. 1;

35 Fig. 3 is a longitudinal section, taken along the line 3—3 in Fig. 1;

Fig. 4 is a plan view of a second form of my invention;

Fig. 5 is an enlarged partial plan view; 40 Fig. 6 is a partial transverse sectional elevation, taken along the line 6—6 in Fig. 5;

Fig. 7 is a partial longitudinal section, taken along the line 7—7 in Fig. 5; and

45 Fig. 8 is a plan view of a design produced by the use of my improved screen.

Referring particularly to Figs. 1 to 3, I have shown a sand obstructing device or screen, comprising a rectangular frame 50 formed of side members 10 and end members 11, said side and end members being rigidly and permanently secured at the corners thereof. A series of parallel adjacent notches or slots 12 are formed in the lower edges of the side members 10 and

are adapted to receive a plurality of cross bars 13 which are a drive fit in the slots 12.

These bars 13 are of relatively slight thickness but are of substantial width, and extend from side to side of the rectangular frame, being secured at their opposite ends in the side members 10. The cross bars 13 are preferably formed of steel and for the most effective operation, the bars 13 are hardened and tempered before being placed in the screen frame.

The frame with its cross bars is placed against the surface of the stone in which a design has been produced by a sand blast and the sand blast is thereafter directed through the bars against the background, before removing the protecting coating of gelatine or other similar material from the face of the stone.

The background will thus be sunk slightly 75 deeper than before, but the portions of the background under or aligned with the cross bars 13 will be left without further depression, thus forming a contrasting background of closely adjacent parallel raised 80 lines of stone, as shown in Fig. 8.

This form of screen has certain advantages over the rectangular mesh wire screen shown and described in the Sanborn and Haslam patent. One of these advantages is 85 the increased sharpness of the lines produced in the background, as the relatively broad side faces of the bars 13 direct the sandblast perpendicularly against the surface of the background, whereas with the wire 90 screen a certain amount of angular approach of the sand was permitted.

I find it to be of substantial advantage to use hardened and tempered or resilient 95 steel bars, as these bars not only resist the wear of the sand blast more effectively, but they also retain their positions more accurately, even when the temperature of the bars is substantially raised by the friction of the sand.

Referring now to Figs. 4 to 7, I have shown a second form of screen or sand obstructing device, in which the cross bars 20 are provided with openings 21 at their ends through which extend tie-rods 22. 105 Spacing members or washers 23 hold the cross bars 20 in the desired spaced parallel relation. Rigid end members 24 are also secured by the tie-rods or bolts 22, and these end members, together with the 110

tie-rods 22 and the spacing members 23, firmly clamp the bars 20 together in spaced relation and form a rigid supporting frame for said cross bars.

5 The use and operation of this type of screen or sand obstructing device is identical with that previously described.

Having thus described my invention and the advantages thereof, I do not wish to 10 be limited to the details herein disclosed otherwise than as set forth in the claims, but what I claim is:—

15 1. In a sand blasting apparatus, a sand obstructing device for producing an ornamental back ground, said device being adapted to be interposed in the path of the sand blast adjacent the surface of the work, and comprising a plurality of thin, flat, elongated, steel bars, and means to firmly support said bars substantially parallel and with their flat side faces substantially perpendicular to the surface of the work.

20 2. In a sand blasting apparatus, a sand obstructing device for producing an orna-

mental background, said device being adapted to be interposed in the path of the sand blast adjacent the surface of the work, and comprising a plurality of thin, flat, elongated, steel bars, and means to firmly support said bars in adjacent parallel relation 30 with their side faces substantially perpendicular to the surface of the work, said bars being hardened and resiliently resisting distortion from wear or heat.

3. In a sand blasting apparatus, a sand obstructing device for producing an ornamental background, said device being adapted to be interposed in the path of the sand blast adjacent the surface of the work, and comprising a plurality of thin, flat, elongated, steel bars, and a rigid open rectangular frame having notches in the lower portions of the side frame members, in which notches said bars are inserted with a drive fit.

45 In testimony whereof I have hereunto affixed my signature.

ELROY A. CHASE.
